Patented Nov. 27, 1917.

2 SHEETS—SHEET 2.

Fig. 2.

UNITED STATES PATENT OFFICE.

CHARLES W. BARNETT, OF PHOENIX, ARIZONA, ASSIGNOR OF ONE-HALF TO JOEL E. MEACHAM, OF PHOENIX, ARIZONA.

HEATING SYSTEM FOR AUTOMOBILES, &c.

1,247,783.

Specification of Letters Patent.

Patented Nov. 27, 1917.

Application filed January 2, 1917. Serial No. 140,219.

To all whom it may concern:

Be it known that I, CHARLES W. BARNETT, a citizen of the United States, residing at Phoenix, in the county of Maricopa and 5 State of Arizona, have invented certain new and useful Improvements in Heating Systems for Automobiles, &c., of which the following is a specification.

This invention relates to certain new and 10 useful improvements in heaters for motor vehicles, flying machines, airships, launches and the like, and it has for its objects among others to provide a simplified and improved heating system which in use shall act also 15 as a muffler and in which the construction is such that there is less back pressure on the engine than heretofore and in which the heat is evenly distributed and the clothing of the occupants of the car, the robes, etc., 20 will not be burned by coming in contact with the heating casings.

It has for a further object to provide a 25 heating system by which the front of the car can be heated without heating the back 30 of the car, or vice versa, or both back and front of the car heated at the same time, with complete control of the heat at all, 35 times.

I utilize all or part of the exhaust gases 40 from the motor in the front or back heating chambers or casings separately or both at the same time and provide means to protect the occupants of the car from the extremely heated surfaces.

Other objects and advantages of the 45 invention will hereinafter appear and the novel features thereof will be particularly pointed out in the appended claims.

The invention is clearly illustrated in the 50 accompanying drawings, which, with the numerals of reference marked thereon, form a part of this specification, and in which—

Figure 1 is a view in side elevation with 55 parts in vertical longitudinal section, showing the combined heater and muffler as applied to the engine of an automobile.

Fig. 2 is an enlarged view, partly in elevation and partly in vertical longitudinal section, of the parts constituting the present 50 invention, applied as in Fig. 1.

Fig. 3 is a detail in top plan of a heater 55 casing showing the reticulated support.

Fig. 4 is a top plan with the lining band and reticulated support removed.

Fig. 5 is a vertical section of the rear 55 heater casing, the section being taken as on the line 5—5 of Fig. 3.

Fig. 6 is a vertical section on the line 6—6 of Fig. 3, looking in the direction of the arrows.

Like numerals of reference indicate like parts throughout the different views.

Referring to the drawings, Fig. 1, my present invention is shown as applied to an automobile of otherwise known construction and arrangement of parts, 1 designating the front seat and 2 the rear seat thereof, 3 being the floor of the car, and in this floor I make, in the present instance, two openings 4 and 5, as seen clearly in Figs. 1 and 2, in each of which is disposed a heater casing soon to be described. It is evident that in a single seated car but one of these casings is necessary, and in a car having a greater number of seats a corresponding 75 number of heater casings may be provided.

6 is an exhaust pipe leading from the engine to a control box or heat-distributing element 7 which may be supported in any suitable manner beneath the bottom of the 80 car. This exhaust pipe preferably enters the front end of the control box, while from the other or rear end of said control box there extends a pipe 8 which communicates with the interior of a muffler 9, the outlet 10 from 85 which extends rearward beneath the rear of the car. This muffler may be of any well-known or preferred form of construction adapted to serve in the usual way and, hence, no specific illustration or description thereof 90 is deemed necessary.

11 is a cut-out from the control box to the open atmosphere. As shown in Fig. 2, it is disposed substantially at the forward end of the control box and depends therefrom, 95 but this is not essential.

Beneath each opening in the floor 3 I dispose a heating casing. Each heating casing is disposed within an outer casing which is lined with asbestos or an analogous 100 material. In each opening above the heater casing is disposed, flush with the floor, a grating or reticulated support serving to protect the clothing of the occupants of the car, the robes, etc., from direct contact with 105 the heating casings.

Referring to Fig. 6, 12 is an outer casing flanged at its upper edge, as seen at 13, to

rest upon a supporting shoulder 14 around the opening 5 in the floor and within this casing is a lining 15 of asbestos or the like, while a surrounding band or the like 16 of asbestos or the like is supported upon the flange 13 and the asbestos lining 15, as seen in said Fig. 6, and upon this band 16 rests the grating or reticulated support 17, the latter being preferably set within the opening 5 with its upper surface flush with the upper surface of the floor 3.

Within this asbestos-lined casing is a heating casing 18 of less dimensions than the asbestos-lined casing and protected from outside atmosphere by the latter, and being smaller there is an air space 19 at the sides and ends surrounding said heater casing, and as the latter is also supported in an elevated position above the bottom of the asbestos-lined casing there is also an air space 20 beneath the bottom of the heater casing so that all of the radiated heat from the bottom of the heater casing comes up into the car which enables me to get and protect all the heat radiated from all the surfaces of the heater casing. In the present instance, the heater casing is shown as held in such elevated position by means of the intake pipe 21 and the outlet pipe 22 of said casing, as seen clearly in Fig. 6.

In the heater casing 18 I arrange a vertical partition 23 extending lengthwise thereof, as seen in Fig. 4, and terminating at a short distance from the end of said casing opposite where the heat enters the casing, as indicated at 24 in Fig. 4, so as to compel a complete circulation of the heated gases through the heating casing and providing a uniform heat throughout the casing.

In the opening 4 in the floor of the car at the rear seat is a similar outer casing 25, as seen in Figs. 1, 2 and 5, the same being flanged, as at 26, and having an asbestos lining 27 with an asbestos band 28 and a grating or the like 29, the same as in the form illustrated in Fig. 6 and just specifically described. 30 is a heater casing within the asbestos-lined casing 25 having a longitudinally extending vertical partition 31 terminating at a short distance from the end of the casing farthest removed from the point of inlet through the inlet 32, seen in Fig. 2, so as to provide a passage 33 from one side of the partition to the other at the end of the casing, as clearly shown in Fig. 5. The intake pipe 32 extends from the rear end of the control box 7 and empties into the heater casing 31, as will be readily understood upon reference to Figs. 1 and 2. In this instance the heating chamber 30 is supported at a distance above the bottom of the asbestos-lined casing by means of a block or the like 34 and the outlet pipe 35 from the end of said casing 31 to the open-atmos-

sphere. This leaves an air space 36-37 around the sides, ends and bottom of the heating casing or chambers 30 for the purpose above set forth in connection with the heating chamber 18.

The partition within the heating casing or chamber serves a further function of diverting the heated gases through the pipe 22 to the control box 7, from whence it may be diverted to the back heater casing through the pipe 32 by means of the baffle plate 38, see Fig. 2. 39 and 40 are similar baffle plates for the pipes 21 and 22, as seen in Fig. 2, all of said baffle plates being disposed within the control box 7 and suitably hinged, as shown, these baffle plates being controlled in a manner soon to be described.

41 is a shaft mounted transversely in the cut-out 11 and carrying within said cut-out a valve 42, as seen best in Fig. 2, adapted to control the said cut-out, and on this shaft 41 is an arm 43 mounted intermediate its ends and to one end thereof is connected a cord or the like 44, the other end of which is connected, as at 45, in any suitable manner with a foot pedal 46, all as clearly illustrated in Fig. 1. 47 is a spring or wire or the like containing a spring portion which is attached at one end to the other end of said arm and its other end to some fixed support, as, for instance, the casing 12, as seen in Figs. 1 and 2.

The baffle plate or flap valve 38, pivotally mounted at 48, is controlled by means of the arm 49 attached intermediate its ends to said pivot and having connected thereto one end of the rod or other connection 50, the other end of which is adapted to engage over one of the hooks or the like 51 on the rear of the front seat, as seen best in Fig. 1. The 105 other end of said arm 49 has connected therewith a member 52 embodying a spring portion, as shown in Figs. 1 and 2, the other end of said member being connected to said fixed part, as the floor of the car, as seen in Fig. 1.

The rod 50 is guided by a roller 53 suitably fixed, as seen in Fig. 1.

The baffle plates or flap valves 39 and 40 are controlled simultaneously in the following manner: The valve 39 is pivotally mounted, as at 54, while the valve 40 is pivotally mounted, as at 55, the said pivots being arranged at adjacent ends of the said valves, as seen best in Fig. 2. Fast on the pivots of these valves are the segmental gears 56 and 57 respectively, the said gears being adapted to mesh with each other, as seen in Figs. 1 and 2, while fast upon the pivot 55 is an arm 58, to one end of which is connected one end of a rod or the like 59 which, after being guided by the roller 60, extends upward, to a point at the front of the front seat and adapted to be engaged over one of the hooks or the like 61 attached 125 130

to the front end of the seat, all as seen clearly in Fig. 1. It is evident that other means may be provided for holding the member 59 in its adjusted position. The same is true of the manner of holding the member 50 just described.

62 is a spring connected at one end to the other end of the arm 58 and its other end connected in any suitable manner to some fixed part, as, for instance, the floor of the car or any convenient part. These baffle plates acting simultaneously and in unison control the intake and outlet of heated gases from the engine to and from the heating casing 18, as will be readily understood upon reference to Fig. 2. The baffle plate 38 controls the intake to the heater casing 30.

It is evident that the asbestos lining to the casings may be held in position in any suitable manner, by screws or the like. The tops of the heater casings may be secured in position in any well-known way, either frictionally or by positive means, as may be found most expedient.

25 It will be evident that the springs 52 and 62 serve to normally close the baffle plates upon which they act and also that the spring 47 serves to normally keep the valve 42 of the cut-out in its closed position.

30 The baffle plates 38, 39 and 40 may be swung to any desired angle so as to have complete control of the amount of heat admitted to the front heater casing, as well as that which shall pass to the control box, and also the heat that passes to the control box from the front casing can be utilized in the back casing. When the baffle plate 40 is open at any angle to admit heat to the front heater casing, the baffle plate 39 from

35 the front heater casing to the control box is actuated by the segmental gears and swung to a corresponding angle to admit the exhaust heat from the front heater casing to the control box. Now, supposing that we

40 get enough heat in the front heater casing with the baffle plates 39 and 40 swung at an angle of 45° in the control box, part of the heat passes to the baffle plate 38 which is dropped down on the bottom of the control box, which diverts the heated gases that may pass the baffle plates, and also what heated gases pass down through the pipe 22 from the front heater casing is all utilized in the back heater casing. Now, should we

45 have too much heat in the back heater casing, the baffle plate 38 is raised, closing the opening into the pipe 32, or set at any angle desired to divert just what heat is needed, letting part of the heat pass out through the pipe 8 to the muffler 9.

It is well-known that there is more heat required in the back casing than in the front casing because the front of the car is more or less heated from radiated heat from the engine. If no heat is required in the front

heater casing and is required in the back heater casing, the baffle plates 39 and 40 are swung up against the top of the control box, closing the pipes 20 and 21 and the baffle plate 38 is swung to the desired angle 70 to divert the required heat through the pipe 32 to the back heater casing. Any heated gases admitted to the back heater casing, after having passed through the same, are exhausted through the pipe 35 to the open 75 air.

When heat is not required in either of the heater casings, the baffle plates 38, 39 and 40 are all swung upward against the top of the control box, closing the openings 80 to the pipes 21, 22 and 32 and then the heated gases pass directly through the control box and through the pipe 8 to the muffler 9 and thence by way of pipe 10 to the open air.

When the heated gases are diverted through the heater casings and exhausted through pipe 35 to the open air, the heating system acts as a muffler, and by means of the cut-out valve 42 we have a direct cut-out 90 to the open air near the engine, the same being controlled by the mechanical means above described disposed within convenient reach of the operator. The muffler does not constitute a part of the heating system and when the heating system is employed it acts as a muffler and there is less back pressure on the engine than when gases are running through the ordinary muffler as there are more expanding chambers in the heating 100 system than in most mufflers. The reticulated covers to the casings of the heating casings serve to protect the garments of the occupants of the car, as well as the robes and the like, and in summer time they can 105 be covered by a carpet or rug.

Importance is attached to the asbestos-lined casings which prevent the cold air from cooling the heating casings, thus insuring greater and more uniform heat. The 110 reticulated covers or gratings are also deemed of importance for otherwise when the heating casings get hot enough to make the car comfortable they would be so hot that anything coming in contact therewith would be burned, such, for instance, as shoes, rubbers, dresses, etc. Also by the arrangement of the heating casings within the asbestos-lined casings with air spaces all around I get the direct benefit of all radiated heat from all surfaces up into the car. Importance is also attached to the fact that by my present construction I may admit heat to the front casing alone, to the rear casing alone, or both simultaneously, or can 120 shut them both off so that no heat passes to either, the heated gases passing directly through the control box and escaping through the muffler.

Modifications in details may be resorted 130
